(57) **CLAIM**

The ornamental design for a sterilization deodorizer, as shown and described.

DESCRIPTION

FIG. 1 is a front perspective view of a sterilization deodorizer showing my new design;

FIG. 2 is a rear perspective view thereof;

FIG. 3 is a front perspective view thereof;

FIG. 4 is a rear perspective view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a top plan view thereof;

FIG. 10 is a bottom plan view thereof; and,

FIG. 11 is an enlarged cross-sectional view taken along the line 11-11 of FIG. 5 and viewed in the direction of the arrows, omitting internal mechanism.

The broken lines shown in the drawings illustrate unclaimed portions of the sterilization deodorizer and form no part of the claimed design. All contour lines shown in the drawings are lines representing surfaces of the solid body, and form no part of the claimed design.
